CAN CARRIER CLIP

James C. De Shazor, Jr., 3314 Coy Drive,
Sherman Oaks, Calif.

Filed Apr. 22, 1963, Ser. No. 74,548

Term of patent 14 years

(Cl. D58—26)

FIG. 1

FIG. 2

FIG. 3

FIG. 4

FIG. 5

FIG. 6

I claim:

The ornamental design for a can carrier clip, as shown.
